[57]**ABSTRACT**

This disclosure relates to substituted hydrazines, e.g. N-(2,6-dichlorobenzylidene)-N'-amidino hydrazine. These compounds are useful in the treatment of the pain of the migraine syndrome.

10 Claims, No Drawings

SUBSTITUTED BENZYLIDENE HYDRAZINES AS
ANTI-MIGRAINE SYNDROME AGENTS

This application is a continuation-in-part of application Ser. No. 322,623, filed Jan. 11, 1973, now abandoned.

This invention relates to the pharmaceutical activity of hydrazine derivatives. More particularly, this invention concerns the use of 2 and/or 6-substituted benzylidene hydrazines in the treatment of the pain of the migraine syndrome in mammals.

The active agents with which this invention is concerned may be represented by the following structural formula:

wherein

R₁ and R₂ are independently hydrogen, halo having an atomic weight of 19 to 36, e.g., chloro or fluoro, methyl, or trifluoromethyl,

R₃ is hydrogen,

R₄ is hydrogen or OH, or

R₃ and R₄ together are -(CH₂)₂-, provided that at least one of R₁ or R₂ is other than hydrogen, and pharmaceutically acceptable acid addition salts thereof.

The compounds of formula (I) above are known and may be prepared according to methods disclosed in the literature from known materials, for example, see U.S. Pat. No. 3,516,995, U.S. Pat. No. 3,591,636 and U.S. Pat. No. 3,658,993. The compounds of formula (I) may also be described as 2 and/or 6-substituted benzylideneaminoguanidines. The present invention only contemplates the novel use of such compounds in pharmaceutical applications, particularly in the treatment of the pain of the migraine syndrome. The above mentioned activity of these compounds is indicated by their activity in the cat given typically 0.01 to 1 mg/kg of active compound intravenously and tested for its constrictive effect upon blood flow. The arterial segments of the cat in which blood flow is to be measured are exposed, and a tight ligature is tied around the upper portion of the artery and the lower portion cannulated with saline-filled plastic tubing of sufficient diameter to snugly enter the artery. The other end of the tubing is connected to another previously cannulated artery from which blood flows under arterial pressure into the arterial segment which is under study. A blood flow transducer is interposed in the tubing to measure the flow. A pressure transducer is connected lateral to the flow in order to measure the driving pressure. From 0.0001 to 0.01 mg/kg of Ergotamine Tartrate or Vasopressin are first injected intravenously to serve as a reference. The active agent is then injected intravenously and the resistance to flow and the effects of the active agent on resistance are measured by calculating the resistance to flow (R) as R = Pressure/Flow, expressed as percent change in resistance (R).

The effect of the compounds 1 in the above-indicated test is similar to that of the known anti-migraine syndrome drug "Catapresan".

For such usage, the compounds may be administered orally or parenterally as such or admixed with conventional pharmaceutical carriers. They may be administered in such forms as tablets, dispersible powders, granules, capsules, syrups and elixirs and parenterally as solutions, suspensions, dispersions, emulsions and 5 the like, e.g. a sterile injectable aqueous solution. The compositions may contain one or more conventional adjuvants, such as sweetening agents, flavoring agents, coloring agents and preserving agents, in order to provide an elegant and palatable preparation. Tablets may 10 contain the active ingredient in admixture with conventional pharmaceutically acceptable excipients, e.g., inert diluents, such as calcium carbonate, sodium carbonate, lactose and talc, granulating and disintegrating agents, e.g., starch and alginic acid, binding agents, 15 e.g., starch, gelatin and acacia, and lubricating agents, e.g., magnesium stearate, stearic acid and talc. The tablets may be uncoated or coated by known techniques to delay disintegration and absorption in the gastrointestinal tract and thereby provide a sustained action 20 over a longer period. Similarly, oral liquids, e.g., suspensions may contain the active ingredient in admixture with any of the conventional excipients utilized for the preparation of such compositions, e.g., suspending agents (methylcellulose, tragacanth and sodium alginate) wetting agents (lecithin, polyoxyethylene stearate and polyoxyethylene sorbitan mono-oleate) and preservatives (ethyl-o-hydroxybenzoate). Capsules 25 may contain the active ingredient alone or admixed with an inert solid diluent, e.g., calcium carbonate, calcium phosphate and kaolin. The injectable compositions are formulated as known in the art. These pharmaceutical preparations may contain up to about 90% of the active ingredient in combination with the carrier or adjuvant. 30 Furthermore, the compounds of formula (I) may be similarly administered in the form of their non-toxic pharmaceutically acceptable acid addition salts. Such salts possess the same order of activity as the free base, 35 which are readily prepared by reacting the base with an appropriate acid and, accordingly, are included within the scope of the invention. Representative of such salts are the mineral acid salts, such as the hydrochloride, hydrobromide, sulfate, phosphate and the like and the organic acid salts, such as the succinate, benzoate, acetate, p-toluenesulfonate, benzene-sulfonate, maleate, malate, tartrate, methanesulfonate, cyclohexylsulfonate and the like. 40 The effective dosage of active ingredient employed in the alleviation of the pain of the migraine syndrome 45 may vary depending on the particular compound employed, the manner of administering and the severity of the condition being treated. However, in general, satisfactory results are obtained when the compounds of formula (I) are administered at a daily dosage of from about 0.0001 milligrams to about 10 milligrams p.o. per kilogram of animal body weight. The compounds are preferably given in divided doses two to four times a day, or in sustained release form. For most large 50 mammals, the total daily dosage is from about 0.007 milligrams to about 50 milligrams. Dosage forms suitable for oral use comprise from about 0.002 to about 55 25 milligrams of the active compound in intimate ad-

mixture with a solid or liquid pharmaceutically acceptable carrier or diluent.

Compounds of formula (I) which can be used as the active ingredient include the following:

- a. 2,6-dichlorobenzaldehyde-2-imidazolin-2-yl hydrazone,
- b. N-(2-chloro-6-fluorobenzaldehyde)-2-imidazolin-2-yl-hydrazone hydrogen iodide;
- c. 2,6-dimethylbenzaldehyde-2-imidazolin-2-yl hydrazone hydrochloride;
- d. 1-(2,6-dichlorobenzylideneamino)-3-hydroxyguanidine hydrochloride;
- e. 1-(2-chlorobenzylideneamino)-3-hydroxyguanidine hydrochloride, and
- f. 1-(2,6-dichlorobenzylideneamino) guanidine hydrochloride.

The preferred pharmaceutical compositions from the standpoint of preparation and ease of administration are solid compositions, particularly hard-filled capsules and tablets containing from about 1 to 10 milligrams of the active ingredient.

EXAMPLES 1 AND 2

Tablets and Capsules Suitable for Oral Administration

Tablets and capsules containing the ingredients indicated below may be prepared by conventional techniques and are useful in treating the pain of the migraine syndrome at a dose of one tablet or capsule 2 to 4 times a day.

Ingredient	Weight (mg) tablet	Weight (mg) capsule	35
1-(2,6-dichlorobenzylideneamino)-3-hydroxyguanidine hydrochloride	10	10	
tragacanth	10	—	
lactose	237.5	290	
corn starch	25		
talcum	15		
magnesium stearate	2.5		
Total	300 mg.	300 mg.	40

Tablets and capsules useful in the treatment of the pain of the migraine syndrome may be prepared in a similar manner using compounds a) to c) and e) and f) above as the active ingredient.

EXAMPLES 3 AND 4

Sterile Suspension for Injection and Oral Liquid Suspension

The following pharmaceutical compositions are formulated with the indicated amount of active agent using conventional techniques. The injectable suspension and the oral liquid suspension represent formulations useful as unit doses which may be administered in the treatment of the pain of the migraine syndrome. The injectable suspension is suitable for administration once a day whereas the oral liquid suspension is suitably administered 2 to 4 times per day for this purpose.

Similarly, injectable suspensions and oral liquid suspension useful in the treatment of the pain of the migraine syndrome may be prepared in the same manner using compounds a) to c) and e) and f) above as the active ingredient.

What is claimed is:

1. The method of treating the pain of the migraine syndrome, which comprises administering to a mammal in need of said treatment a migraine syndrome pain relieving effective amount of a compound of the formula

wherein

R_1 and R_2 are independently hydrogen, halo having an atomic weight of 19 to 36, methyl, or trifluoromethyl,

R_3 is hydrogen,

R_4 is hydrogen or OH, or

R_3 and R_4 together are $-(\text{CH}_2)_2-$, provided that one of R_1 or R_2 is other than hydrogen, or a pharmaceutically acceptable acid addition salt thereof.

2. The method of claim 1 wherein the compound is administered at a daily dosage of from 0.007 milligrams to about 50 milligrams.

3. The method of claim 1 wherein the compound is administered in a unit dosage form comprising said compound to the extent of from 0.002 to about 12.5 milligrams per unit dosage.

4. The method of claim 1 wherein the compound is 1-(2,6-dichlorobenzylideneamino)-3-hydroxyguanidine.

5. The method of claim 1 wherein the compound is 1-(2,6-dichlorobenzylideneamino)guanidine.

6. The method of treating the pain of the migraine syndrome, which comprises administering orally to a mammal in need of said treatment a migraine syndrome

Ingredients	Weight (mg) injectable suspension	Weight (mg) liquid suspension	65
1-(2,6-dichlorobenzylidene-			

pain relieving effective amount of a compound of the formula:

wherein R₁, R₂, R₃, R₄ and the proviso are as defined in claim 1, or a pharmaceutically acceptable acid addition salt thereof.

7. The method of claim 6 wherein the compound is administered at a daily dosage of from 0.007 milligrams to about 50 milligrams.

8. The method of claim 6 wherein the compound is administered in a unit dosage form comprising said compound to the extent of from 0.002 to about 12.5 milligrams per unit dosage.

9. The method of claim 6 wherein the compound is 10 1-(2,6-dichlorobenzylideneamino)-3-hydroxyguanidine.

10. The method of claim 6 wherein the compound is 1-(2,6-dichlorobenzylideneamino)guanidine.
